US0D1060241S

(12) **United States Design Patent** (10) **Patent No.:** **US D1,060,241 S**
(45) **Date of Patent:** **** Feb. 4, 2025**

(54) **WIRELESS CHARGING CASE**

(71) Applicant: **Shenzhen Baizhiyuan Trading Co., Ltd.**, Shenzhen (CN)

(72) Inventor: **Hanzhong Wang**, Jieyang (CN)

(73) Assignee: **Shenzhen Baizhiyuan Trading Co., Ltd.**, Shenzhen (CN)

(**) Term: **15 Years**

(21) Appl. No.: **29/968,273**

(22) Filed: **Oct. 15, 2024**

(51) LOC (15) Cl. **13-02**

(52) U.S. Cl.

USPC **D13/108**

CLAIM

The ornamental design for a wireless charging case, as shown and described.

DESCRIPTION

FIG. 1 is a bottom, front and right side perspective view of a wireless charging case, showing my new design; FIG. 2 is a top, rear and left perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof. The evenly broken lines show the features of the wireless charging case that form no part of the claimed design.
